ADVERTISING CARD DISPLAY SIGN

Edward Fish, New York, N. Y.

Application May 18, 1936, Serial No. 80,259

9 Claims. (Cl. 40—36)

This invention relates to advertising signs and more particularly is directed to an improvement in the construction of signs for incorporating therein a plurality of advertising cards, said signs having novel means for automatically changing the cards displayed on opposite sides of the sign intermittently at desired time intervals.

The object of this invention is to generally improve advertising signs of the character described which shall comprise few and simple parts that are readily assembled to form a construction which will give reliable automatic operation for intermittently changing advertising cards incorporated therewith at desired time intervals, which shall be relatively cheap to manufacture yet form a neat and attractive structure, and which shall be practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawings in which is shown one of the possible illustrative embodiments of this invention,

Figure 1 is a front elevational view of an advertising card display sign, constructed to embody the invention partly broken away to show certain features of the interior construction.

Figure 2 is a top plan view of the improved sign shown in Figure 1, showing the top cover broken away to expose part of the interior construction.

Figures 3 and 4 are cross-sectional views taken on lines 3—3 in Figure 2 and lines 4—4 in Figure 1, respectively.

Figures 5 and 7 are fragmentary cross-sectional views taken on lines 5—5 and 7—7, respectively, in Figure 4.

Figures 6 and 8 are fragmentary cross-sectional views taken on lines 6—6 in Figure 5 and lines 8—8 in Figure 7, respectively.

Figure 9 is a detail view corresponding to a cross-sectional view taken on lines 9—9 in Figure 3, showing the position of the flexible carrier or snake member on which advertising cards are mounted during automatic intermittent changing thereof.

Figure 10 is a fragmentary cross-sectional view similar to Figure 9, showing the position of said carrier or snake member on the completion of the

automatic intermittent changing of the advertising cards.

Figure 11 is a front elevational view of the flexible carrier or snake member on which the advertising cards are mounted removed from the sign.

Figure 12 is a side elevational view of the flexible carrier or snake shown in Figure 11, and

Figures 13 and 14 are fragmentary cross-sectional views taken on lines 13—13 and 14—14 in Figure 11.

Referring now to the drawings, 20 denotes an advertising sign of the character described embodying the invention. In the form here shown, said sign includes automatic means for intermittently changing a plurality of advertising cards incorporated in the sign and displayed on opposite sides thereof. As seen from Figures 1 to 8, inclusive, said sign 20 preferably is mounted on a base or foot board member 21 and has a casing 22 formed with an upright front wall 22a provided with a window opening 22b, an upright rear wall 22c having a window opening 22d, and upright end walls 22m, 22n of semi-circular cross-sectional shape, said casing 22 being provided with a top closure plate 22e having air circulating vents 22k. The front opening 22b and rear opening 22d may be provided with a suitable transparent closure, such as glass windows 23. The opposite upright end walls 22m, 22n of said casing 22 may be formed with outwardly extending ribs 22g for reinforcing the casing structure 22 and to provide an ornamental trimming thereof, said ribs 22g connect with outwardly projecting border portions 22h extending about the rim of the window opening 22b and 22d, as is shown in Figure 1.

The foot board member 21 and said casing 22, fitted with the windows 23 as described above, are thus seen to form a neat and attractive appearing structure for completely enclosing the movable and stationary parts of an automatic mechanism which carries and changes one of a plurality of advertising cards C displayed at each of the front and rear windows 23.

The advertising cards C may be either printed or lithographed on the back and the front of a suitable sheet material such as cardboard or metal, and may be printed on one side, or two cards C assembled back to back, said cards C being mounted on a flexible carrier or snake member 30 as shown in Figures 11 to 13, inclusive. Said carrier or member 30 may comprise a pair of spaced uprights 31, each having a longitudinally extending channel 31a, said uprights 31 being

interconnected by a series of links 32, each also having a longitudinally extending channel 32a. Said links and uprights are flexibly connected together through suitable hinging means, such as 5 pivoting rivets 33. The links 32 are made short enough so that they will readily conform in curvature to the radius of a guiding means, in the manner hereafter described. Uprights 31 are spaced to conform to the length of the advertising 10 cards C to be displayed and are of a height to correspond to the width of such cards.

Each of said uprights 31 has outwardly projected therefrom in the plane of the links 32, an ear 34 which carries to project downwardly 15 therefrom a roller 35. As shown in Figure 14, the roller 35 is journalled on a pin shaft 36, which in turn is riveted at 36a to the ear 34. A spacing collar 37 is provided between the roller 35 and the ear 34 for positioning the roller at a desired 20 distance down from said ear 34. The extreme upper end portions 31a of each of the uprights 31 are preferably enlarged and are of circular cross-sectional shape to serve as a spacing means. The lower end portions 31b of said uprights adjacent 25 to the ear 34 are also of enlarged shape to correspond to the width of the links 32 for the same purpose.

To retain the cards C from being accidentally 30 displaced from their seated position in the channels 31a of the uprights 31 and link channels 32a, suitable means are provided, as for example, a spring strip 38 which is riveted at 38a and carries adjacent the end 38c thereof opposite said rivet 38a, a piercing prong 38b, the latter being 35 adapted to enter an opening 31c provided in each of the uprights 31, just below the enlarged end 31a thereof. Said prongs 38b are adapted to pierce the cards C to securely retain the same in their seated positions in the channels 31a and 40 32a. For conveniently releasing the spring strip 38, the extreme end 38c thereof opposite anchor end 36a, may be suitably formed to provide a finger gripping means. The strip 38 may be flexed for withdrawing the prongs 38b from the opening 45 31c to release the cards C for removal thereof from the carrier 30.

Normally a plurality of carrier members 30 with the cards C mounted thereon are positioned 50 in a group or stack in an upright parallel relation with the enlarged ends 31a and 31b thereof in abutment, the outwardly facing cards C on the end carriers 30 being in register with the front and rear openings 22b and 22d and are visible through the windows 23, as is clearly seen from 55 Figures 1 to 4, inclusive.

The stacked carriers 30 have the bottom or under surfaces of the links 32 and upright ends 31b resting on a platform plate 40 of inverted U-shaped cross-section, as is shown in Figures 1 60 and 3. Said plate 40 may be reinforced by any suitable means, such as spaced triple U-shaped members 41 which have the mid-sections of each thereof 41a secured by means of rivets 42 to said plate 40, the adjacent offset sections 41b of each 65 member 40 being secured to the base 21 by any suitable means such as bolts 43 as is clearly shown in Figure 3.

Extending along the inner side of upper rims 70 of each of the openings 22b and 22d, under the cover plate 22e, there are provided guiding means in the form of inverted reflector channel members 44, each of said channel members having its innermost side flange 44a covered with a sound absorbing resilient material 45 to serve as guiding 75 means for the upper end portions 31a of the

carrier 30. Said channel members 44 have fitted therein a tubular type of electric bulb or lamp 46 which has suitable clip terminals 46a connected in circuit with suitable wiring 47. As is seen from Figures 2 and 3 said electric bulbs 46 5 serve to illuminate the adjacent surface of an advertising card C. It should be noted that the positions of the end carriers 30 may be such that the visible advertising cards C are retained slightly out of the normally perpendicular plane, the 10 surfaces of said cards being positioned to positively intercept the light beams projected from the bulbs 46, as is shown in Figure 3. The inner side flange 44a of the channel members 44 are interconnected by a curved wall 44b to serve as a 15 continuous guiding means for the upper carrier portion 31a. Said wall 44b may be covered with the resilient material 45 like that applied to flange 44a.

The carriers 30 are moved from the rear to the 20 front side for exposing the opposite sides of the cards C, in the manner hereinafter described, by means of a continuously running endless chain 50 which rides in a U-shaped track 51. Said track is located beneath the plate 40 and extends 25 along opposite sides at spaced distances and below the bevel of the openings 22b and 22d. Said chain 50 at one turn rides on a large idler sprocket 52 which is mounted on a shaft 52a supported on a mounting 52b and secured by bolts 52c which 30 project down from the plate 40c, as is shown in Figure 5. The other turn of the chain 50, opposite that engaging with the idler sprocket 52 is driven from a small drive sprocket 53. Said drive sprocket 53 is continuously rotated by any 35 suitable power means, as for example, an electric motor M having an intermediate suitable reduction gear transmission 60 in the form, as here shown, of a worm and wheel 60a, the worm being mounted to turn with a shaft 60b of the 40 motor M, and the wheel being mounted on a stub shaft 60c and connected through a sleeve 60d with a bevel gear 60e. The latter engages with a complementary bevel gear 60f secured to turn with shaft 60g, carrying the drive pinion 53. (See 45 Figures 1 and 4.)

A pedestal casing 61, enclosing the reduction gear transmission 60, may be provided to rigidly support the motor M on extension portion plate 50 40a of the plate 40 with the shaft 60b thereof 55 in a vertical extending position. Bolts 62 serve to secure the motor pedestal casing 61 to said plate portion 40a, the latter being provided with end flanges 40b which may be bolted, as at 63, to the casing 22, as is shown in Figure 1. The stub shaft 60c extends in a horizontal direction and has one end thereof rigidly supported at 61a from the casing 61 as shown in Figure 4. To align chain 50 at said last turn in passing from the drive sprocket 53 to a straightway portion 50a of 60 the track 51, a small idler gear 53a is provided, said gear being mounted to turn on a shaft 53b extending down from the platform plate portion 40a and positioned with respect to said drive sprocket 53 and the large idler sprocket 52, as 65 shown in Figure 9.

An extension plate portion 40c, situated on the opposite end of plate 40 with respect to plate portion 40a above the sprocket 52, carries an upright inner tubular guiding member 70 of reversed 70 D shape cross-sectional shape. The flat side wall 70a of said member 70 extends along a rim edge of the plate 40 in parallel relation to a slideway 40e located between plate 40 and plate portion 40c, said slideway 40d engaging roller collars 75 75

of the grouped parallelly aligned carriers 30. The semi-circular wall 70b of said member 70 is concentric with the large sprocket 52 on which the chain 50 turns, as shown in Figures 9 and 10.

5 The rim edge of platform plate 40, the slide-way 40e between said plate 40 and plate portion 40a, and the curved rim edge 40f of the plate portion 40a provide an endless guiding means for the carriers 30 by engaging and retaining one of 10 the roller collars 37 in operative position with respect to the movement of the chain 50 around the sprocket 52. A similarly constructed slide-way 40g is provided between the rim edges of platform plate 40 and plate portion 40b.

15 The chain 50 has secured to turn therewith a puller 50a and side pusher 50b which trails the puller 50a by a distance slightly greater than the length of a carrier 30. Said puller 50a extends up from the chain 50 and its path of movement is such as to engage with a leading roller 35 of the carrier 30 which is positioned at rest with a card C thereof visible through window 23 at rear opening 22d. Said carrier 30 when being moved by a puller 50a in the direction of the arrow shown in Figure 9, from said position of rest, passes around the first turn with the chain 50 riding on the large idler sprocket 52 until the card C in said carrier 30 registers with the front opening 22b, said carrier 30 being then automatically disengaged from the puller 50a and chain 50 in the manner hereafter to be described.

20 The carrier 30 is guided in its movement by the engagement of the collars 37 above each roller 35 with the slideways along the rim edges of platform plate 40 and in 40d and 40g. The rollers 35 being smaller in diameter than the ears 34 or the collars 37 prevent any accidental displacement from said guiding slideways.

In Figures 2, 3, 4, 5 and 7, there is shown a sign 25 accommodating ten carriers 30 in stacked or grouped parallel alignment between the front opening 22b and the rear opening 22d, said carriers 30 having mounted thereon either ten display advertising cards C printed on the front and reverse side of each or twenty cards printed on one side and two such cards C positioned in back to back relation in each of the carriers 30. Extending along the inner front wall 22a of the casing 22 just below the level of the lower rim opening 22b, there is provided a press member 80, said member forming part of telescoping head 81, which is held resiliently in extended position by any suitable means, such as spaced compression springs 82 for reciprocating the head 81 with 30 in a frame 83. The head 81 aligns with the lower end 31b of the uprights of the carrier 30 and with the links 32, and serves to provide a constant pressure against the grouped parallelly aligned carriers 30 to resiliently urge the said carriers 35 towards the rear casing window opening 22d. To limit said parallelly aligned carriers in their movement for proper cooperation with the chain 50 and puller 50a there is provided a stop abutment projection 82, carried on the plate 40 as shown in Fig. 3.

35 Between platform plate 40 and plate portions 40a and 40c, are the spaced cross slideways 40d and 40g, wherethrough the collars 37 of the rollers 35 extend, to permit said rollers to freely pass along below the level of the platform 40, while the carriers 30 with the cards C are moved along on the upper side of said platform plate 40.

40 From the drawings and the above description the operation of the improved sign 20 will now be apparent. The cards C are first mounted in

each of the carriers 30 with the sides and bottom of the cards positioned within the channel 31b and 32a of the uprights 31 and links 32, respectively. To insert these cards C in place, the spring members 36 are flexed outwardly so that 5 the prong 36b is withdrawn from the openings 31c leaving a free passage for the insertion of the cards C into said channels of the carriers 30. The spring member 36 is then released and each prong 36b is pushed to pierce the cards C so as 10 to enter the openings 31c thereby releasably retaining the cards C in a mounted position in the carriers 30, as is clearly shown in Figures 11 to 13, inclusive.

15 Preferably the opening 31c in the carrier uprights 31a are made large enough to permit considerable play or free movement of the prong 36b therein. This freedom of movement is desirable since on flexing two cards C mounted in a carrier 30 while passing with the chain 50 around 20 the sprocket 52 on the first turn free movement of the prong 36b eliminates any tendency of inner curved card C to buckle with respect to the outer curved card C.

25 Ten of the carriers 30 may then be positioned in abutment and grouped in parallel alignment, as shown in Figure 2, so that the side of the card C in the carrier 30 adjacent to the rear opening 22d is fully exposed to view through the window 23 and the side of the card adjacent to the front opening 22b is fully exposed to view as is seen through the front window 23. The press head 81 will then be just short of the fully extended position abutting the adjacent carrier 30 as is shown in Figures 3 and 4, and the carrier 30 adjacent the rear opening 22d will be in abutment 30 with the stop projection 84.

35 By throwing a switch S (see Fig. 2) in an "on" position, power is supplied to the motor M, from a suitable source (not shown) through wiring 40 47 which includes in circuit the lamps 46. Said motor M, through the worm and wheel 60a and the bevel gears 60e and 60f of the transmission 60 rotates the drive sprocket 53 for turning the chain 50 to run on the tracks 51, the idler sprockets 52 and 53a being rotated by the passage of the chain 50 thereon. As the puller 50a reaches the leading roller 35 on the carrier 30 positioned adjacent the rear opening 22d, said puller 50a engages with the roller 35 and moves the carrier 30 in the direction of the arrow, as shown in Figure 9. Said carrier 30 continues to move with the chain 50 around the sprocket 52 and between the inner curved wall 70b and an outer curved wall 87 spaced from the wall 70b as shown 50 in Figures 1, 2, 4, 8 and 9. The carrier 30 with the cards C in making the turn with the chain 50 around the sprocket 52 pivot the links 32 of said carrier 30 and flex the advertising cards C. 55

60 Where two cards C are used back to back, the card C which was visible at the rear opening 22d through the window 23 is now moved around by the carrier 30 until the said card C is in register with the front openings 22b. The roller collar 37 on the leading end of said carrier 30 will then 65 have been deflected slightly by a camming portion 40h provided at the entering end of the cross-slideway 40g. The roller collar 37 at the rear end of the carrier 30 then is in alignment with the slideway 40d.

70 Since one of the carriers 30 has been moved out of the parallelly aligned group on the platform 40, there are only nine carriers 30 left in said parallelly aligned position, the arrival of the transferred carrier 30 from the rear opening 22d 75

to the front opening 22b in the wall 22a first causes the press head 81 to retract, that is, pushed back and then to become effective for assisting the pushing of such transferred carrier 30 into an aligning position with the remaining nine carriers. Meanwhile the side pusher 50b carried by the chain 50 has contacted with the rear or trailing roller 35 and moves the collar 37 thereof into the slideway 40d. This action and the pressure exerted by the head 81 forces and retains all ten carriers 30 into abutment on the platform plate 40. There will be exposed to view at the rear opening 22d of the wall 22c the advertising card C opposite to that which was previously exposed to view at the front opening 22b of the wall 22a. Thus it is seen that each of the back to back cards C on a carrier 30 is brought into view first on the rear side, then again on the transfer by the carrier 30 from said rear side to the front side. Thereafter the other side of said card C is brought into view at the rear opening 22d, this cycle being automatically repeated.

The chain 50 moves continuously and since each carrier 30 after being brought in alignment with the front opening 22b is moved by the side pusher 50b and pressure head 81 inwardly away from the path of movement of the chain 50, the puller 50a is left free and does not become effective again until it occupies the same relative position as above described. The puller 50a is freed from the roller 35 at the leading end of the carrier 30 due to the camming movement exerted by the slideway portion 40h.

The above cycle of operation is continuously repeated and the carriers 30, one by one, are intermittently transferred from the rear to the front side of the sign 20 as described above, the speed of the chain 50 being designed to permit the advertising cards C to remain at rest for a predetermined desired time during which the puller 50a is ineffective permitting the legends on the cards C to be read. Should the drive fail or the power to the motor M be cut off for any length of time while a carrier 30 is partly in the position of being transferred from the rear to the front no serious difficulty will be experienced because of any set in the material of the advertising cards C due to bending in being flexed between the curved walls 70b and 87, since said cards C are always unflexed and flattened out by the carrier 30, as the latter is moved by the chain 50 to a straightened out position at the front opening 22b.

As seen in Figure 9 the portion 51a of the track 51 extending adjacent the rear wall opening 22d is nonparallel to the straightway portion of said track 51 extending adjacent the front wall opening 22b, or to the plane of the adjacent carriers 30 on the platform plate 40, that is, the track portion 51a is out of alignment with the carrier 30 which is ready to be transferred from the rear to the front of the sign 20. The angular or side displacement of the track portion 51a carrying the chain 50 which has the puller 50a extending therefrom with respect to the plane of the carrier 30, is such that the puller 50a is brought into engagement with the leading roller 35 after clearing and passing said trailing roller. Thus by the above simple expedient intermittent engaging of the puller 50a and the leading roller 35 is accomplished without the intervention of cams, or other similar operating interconnecting mechanism.

In order to avoid any possible jamming or other disarrangement of the carrier 30 during

the transferred movement there may be provided a ramp deflecting guide 90 which extends from the lower end of the wall 70b on the exit side of the path from the rear to the front side of the sign for causing the front or leading roller 35 to engage with a spring actuated arm or gate 91 pivoted at 92 to swing in the path of movement of the rollers 35 of the carrier 30. As the leading end of the carrier 30 passes around between the wall 70b and 87, it is deflected outwardly by the ramp 90 to swing the arm 91 and thereby permit the passage of the carrier 30 to the front side of the sign. As soon as both rollers 35 of the carrier 30 register with the slideways 40b and 40c, respectively, the side pusher 50b and the press head 81 becomes effective to push the carrier 30 rearward and the gate 91 is then freed and by a spring 93 is again moved from the position shown in Figure 10 to that shown in Figure 9 to serve as a barrier or stop for preventing any back movement of the roller collar 37 from the slideway 40c.

It will thus be seen that there is provided an advertising display card sign in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a device of the character described, a carrier for an advertising card comprising spaced uprights interconnected by links, said uprights and links having channels for receiving edge portions of the card.

2. In a device of the character described, a carrier formed of jointed parts, and means for retaining an advertising card to the carrier flexed and unflexed on movement of said jointed parts.

3. In combination, a carrier and a flexible sheet secured to said carrier, said carrier comprising spaced uprights, links interconnecting said uprights, and means for seating the card between said uprights and on said links.

4. In a device of the character described, a carrier for an advertising card comprising spaced uprights interconnected by links, said uprights and links having channels for receiving edge portions of the card, and means for releasably fastening the cards in said channels.

5. In combination, a carrier, a flexible sheet, said carrier comprising spaced uprights, links interconnecting said uprights, means for seating the card between said uprights and on said links, and releasable means on the carrier for locking the card thereto.

6. In a device of the character described, a carrier for an advertising card comprising spaced uprights interconnected by links, said uprights and links having channels for receiving edge portions of the card, and means on said carrier for engaging a power drive.

7. In a device of the character described, a carrier formed of jointed parts, means for retaining an advertising card to the carrier flexed and unflexed on movement of said jointed parts, and an extension on one of said parts for applying power to move said carrier.

8. In combination, a carrier and a flexible sheet secured to said carrier, said carrier comprising spaced uprights, links interconnecting said uprights, means for seating the card between said uprights and on said links, and a power receiving projection on one of said uprights.

9. In a device of the character described, a carrier for an advertising card comprising spaced

uprights interconnected by links, said uprights and links having channels for receiving edge portions of the card, means for releasably fastening the cards in said channel, and a projection extending from an upright adapted to engage with 5 a chain drive.

EDWARD FISH.
